JOHN GREENWOOD, OF ROCHESTER, NEW YORK.

Letters Patent No. 79,651, dated July 7, 1868.

IMPROVEMENT IN MACHINES FOR CUTTING STAVES.

The Schedule referred to in these Letters Patent and making part of the same.

TO ALL WHOM IT MAY CONCERN:

Be it known that I, JOHN GREENWOOD, of Rochester, in the county of Monroe, and State of New York, have invented a certain new and useful Improvement in Machines for Cutting Staves; and I do hereby declare that the following is a full and exact description thereof, reference being had to the accompanying drawings, making part of this specification.

Figure 1 is a vertical cross-section of the machine.

Figure 2, a diagram, showing the arrangement of the rollers and springs.

Like letters of reference indicate corresponding parts in both figures.

My invention consists in the combination and arrangement of a double set of rollers with the curved ribs, in such a manner as to sustain the stave-bolt without coming in contact with the ribs themselves, leaving thereby a narrow space between the said bolt and the ribs, to allow chips and splinters to pass through without displacing the bolt; also, in the employment of springs, combined with the above, for preventing the staves from dropping back into the machine after being cut from the bolt.

In the drawings, A represents the frame, which is of the usual form, having on the back a series of curved ribs, *a a*, against which the bolt moves as it is carried up on the swinging bed B, to the cutter C.

In the face of each of the curved ribs *a a*, I employ a double set of rollers, *g g*, *h h*, situated alternately on opposite sides, so as to break joints with each other, and setting out a little distance from the ribs, so as to leave a narrow space between the bolt, that rests against the rollers, and the ribs.

One great difficulty in cutting staves in ordinary machines, where no rollers are employed, is caused by the chips and splinters falling on the ribs, thereby throwing the bolt out of position, as it slides over them in moving up to the cutter, thus producing an irregular and imperfect cut of the stave. Another difficulty is, that the splinters become wedged between the edge of the swinging bed and face of the ribs, and obstruct the easy operation of the machine, and render it liable to breakage; and furthermore, the friction of the stave-bolt against the iron ribs streaks and discolors the staves, which renders them unfit for fine work. This is especially the case with oak staves, the sap of which seems to produce a chemical effect in contact with the iron, which stains the wood.

With the use of the double set of rollers, arranged alternately, as above described, so as to leave a narrow space between the bolt and ribs, chips and splinters will fall down in the spaces, and easily work out between the rollers, and drop off without interfering with the bolt, and without obstructing the operation of the swinging bed. This alternate arrangement of the rollers also provides a uniform and continuous bearing or rolling-surface for the bolt in moving up to the cutter, and at the same time preserves the face of the ribs, and prevents streaking and discoloring of the wood.

A set of two or more springs, *k k*, arranged at suitable distances apart, are employed, for the purpose of holding the stave as it is cut from the bolt, and preventing it from falling back when the bolt is lowered.

As the bolt passes up to be cut, the edge of the stave, striking the end of the springs *k k*, forces them back until the stave is cut clear, when the springs, holding its lower edge, prevent it from falling back.

At the inner edge of the swing-bed, I secure a strip of metal, *e*, leaving a groove, *i*, which fills with wood, dust, and fine splinters, for the edge of the cutter C to strike into, and prevent it from dulling, and also to allow the staves to cut clear of the bolt.

I am aware that friction-rollers have been in use for various purposes, and therefore do not claim them broadly.

What I claim as my invention, and desire to secure by Letters Patent, is—

The alternate arrangement, on the face of ribs *a a*, of the double set of rollers *g h*, operating relatively with the swing-bed B and cutter C, substantially as and for the purpose described.

In witness whereof, I have hereunto signed my name in the presence of two subscribing witnesses.

JOHN GREENWOOD.
